ELECTROMAGNETIC TALKING MACHINE

Semi Begun, Berlin, Germany, assignor to C. Lorenz Aktiengesellschaft, Berlin-Tempelhof, Germany, a company

Application June 6, 1935, Serial No. 25,353
In Germany June 9, 1934

4 Claims. (Cl. 242—57)

The invention relates to electromagnetic talking machines of the kind having a tape- or wire-shaped sound record carrier and especially to sound recording and reproducing machines of the Poulsen type, and it is more particularly concerned with those devices of this kind in which the spools furnished with the sound record carrier are arranged in a casing to form an interchangeable set of spools.

5 10 In the novel arrangement the circuit of the motor in order to be closed requires the set of spools to be fitted to the machine, so as to get interrupted whenever the set of spools is removed therefrom.

15 20 One embodiment of the invention is shown by way of example in the accompanying drawing, in which Fig. 1 is a diagrammatic sectional elevation, of the assembled apparatus, only such parts being represented as are necessary for a complete understanding of the invention, and, Fig. 2 is a diagrammatic elevation similar to that shown in Fig. 1 with the record carrier removed from the frame.

25 30 The set of spools comprises a casing 1 and two spools 3, 4 for the sound record carrier not shown, such as a steel tape or wire. 2 denotes the upper part of the machine. To the axle of the spool a screw-threaded spindle 5 is geared by bevel wheels 13. Spindle 5 carries a nut 6 adapted to interrupt either one or the other of two contacts 7, 8 and thereby to open the circuit of a motor 9 which serves to drive the device in a manner not shown but well-known to those skilled in the art. The source of current is designated 10.

35 The contacts 7, 8 serve to cut out the motor as soon as the sound record carrier reaches the end of its movement. To rewind the sound record carrier the spools may be turned back by hand far enough to close the contact 7 (or 8) and thus enable the motor circuit to be closed.

40 Contact 7 is shown as open and contact 8 shown as closed. If now the set of spools 1, 3, 45 4 is lifted from part 2, contact 7 closes since nut 6 then is withdrawn from this contact so as to cease to keep it open. As a result the motor 9 would be started if there were not in accordance with the invention a contact 11 or a contact 12, or both of these contacts as shown by way of example, such contacts being disposed in the motor circuit and closed by studs 14 of the casing 1, so that the motor circuit is interrupted whenever the set of spools is removed from part 50 55 2. Otherwise the sound record carrier might

happen to be driven again on the removal of the set of spools and eventually to be torn.

5 By providing two such contacts, the motor circuit will be interrupted even if the set of spools is removed slantingly with respect to part 2 so as to open either contact 11 or contact 12 first. For instance, if the set of spools is at first lifted at that end shown on the right-hand side of the figure then although contact 11 remains closed the motor will not be started because contact 12 is allowed to open.

10 The invention is useful also without there being contacts such as those denoted by 7 and 8. In this case the advantage is attained that the motor cannot be started after the set of spools 15 has been lifted off. This may be advantageous for example if the construction of the talking machine is such that there are rotating parts adapted to injure the user.

20 What is claimed is:

1. In an electromagnetic talking machine an interchangeable spool unit for carrying a flexible record-bearing filament, an electric drive circuit, a series of contacts serially included in said drive circuit and including two contacts located in such positions as to be adjacent the ends of the spool unit when said spool unit is in its operative position, two contact operating portions on said spool unit adjacent the ends thereof, each of said portions being adapted to close one of the 30 said two contacts in response to the correct positioning of the corresponding end of the spool unit whereby said two contacts are both closed only when said unit is in its operative position.

2. A device according to claim 1 having an element movable in correspondence with the travel of the flexible record-bearing filament, and in which the said series of contacts includes a further contact adapted to be opened by said element.

3. In an electromagnetic talking machine system an interchangeable spool unit adapted to carry a flexible record-bearing filament comprising a framepiece, two spools supported therefrom, a progressively movable element supported from said framepiece and means for progressively moving said element in response to the rotation of said spools, an electric drive circuit, a contact included in said drive circuit and adapted to be actuated in response to the progression of said element when said spool unit is in its operative position so as to open the said drive circuit when a predetermined amount of a flexible filament has been wound off from one of said spools onto the other, a pair of auxiliary contacts located in 50 55 50 55

such positions as to be adjacent the ends of the spool unit when said spool unit is in its operative position, two contact operating portions on said spool unit adjacent the ends thereof, each of said portions being adapted to close one of the said auxiliary contacts in response to the correct positioning of the corresponding end of the spool unit whereby at least one of the said contacts is opened in response to any displacement of the spool unit which is sufficient to bring the said progressive element out of operative relation with the said first mentioned contact.

4. In an electromagnetic talking machine an interchangeable spool unit for carrying a flexible record-bearing filament comprising a framepiece, a first spool and a second spool supported from said framepiece, a progressive element also supported from said framepiece and means for progressively moving said element in response to the rotation of one of said spools whereby said element is moved to a first predetermined point in its path in response to the winding off of a predetermined length of said filament from the first spool onto the second spool and is moved to a second predetermined point in its path in response to the winding off of a predetermined length of said filament from the second spool onto the first

spool; a frame separable from said spool unit; driving means mounted on said frame and adapted to drive one of said spools when the spool unit is in operative relation to said frame; a driving circuit for controlling said driving means; a first and a second switching device included in said circuit and supported from said frame and respectively adapted to be opened in response to the progression of said element beyond said first and said second predetermined points when said switching devices are in operative relation with the path of said element; two widely separated contacts mounted on said frame and located in such positions as to be adjacent the ends of the spool unit when said unit is in its operative position relative to said frame; two contact operating portions on the plate of said spool unit adjacent the ends thereof, each of said portions being adapted to close one of the said contacts in response to the correct positioning of the corresponding end of the spool unit whereby said two contacts are both closed only when said unit is so positioned relative to said frame that said switching devices are operatively in the path of said progressive element.
